UNITED STATES PATENT OFFICE.

FRANK A. SCHIMANSKI, OF RACINE, WISCONSIN.

DEVICE FOR REMOVING PHONOGRAPHIC DISK RECORDS.

972,028.

Specification of Letters Patent.

Patented Oct. 4, 1910.

Application filed May 20, 1910. Serial No. 562,436.

To all whom it may concern:

Be it known that I, FRANK A. SCHIMANSKI, a citizen of the United States, residing at Racine, county of Racine, and State of Wisconsin, have invented a new and Improved Device for Removing Phonographic Disk Records, of which the following is a specification.

My invention relates to an accessory to 10 disk phonographs, and has for its object the production of a device adapted for employment in conjunction with phonographs of the character mentioned to facilitate the removal of the record disks therefrom.

15 A further object is the production of a device of the character mentioned which will be efficient in operation and of simple and inexpensive construction, hence of low cost to manufacture.

20 Other objects will appear hereinafter.

With these objects in view my invention consists in an accessory to disk phonographs characterized as above mentioned and in certain details of construction which will be 25 hereinafter fully described and more particularly pointed out in the appended claim.

My invention will be more readily understood by reference to the accompanying drawing forming a part of this specification, 30 and in which,

Figure 1 is a perspective view of a device embodying the preferred form of my invention, and Fig. 2 is a side elevation of an ordinary disk phonograph illustrating the 35 employment of my device in conjunction therewith.

Referring now to the drawing, 1 indicates the body of the device which is simply an elongated flat bar formed of any suitable 40 material but preferably of wood. Said body is of comparatively thin construction, one end 2 thereof being enlarged or broadened. Said end is provided with a V-shaped slot 3 and the arms 4 thereof are formed 45 tapering in construction toward their outer ends. Provided upon the opposite sides of the arms 4 adjacent the extremities thereof are transversely extending strips 5 of a suitable non-abrasive material, preferably felt 50 or plush. The opposite end 6 of the body 1 is also enlarged, the same being provided

upon its opposite sides with coverings 7 of felt, plush, or any other suitable non-abrasive material. Said end is shown as being in the form of an arrow head, however, this is im- 55 material except in so far as it adds to neatness in design.

In using the device, as shown in Fig. 2, to remove a record disk, the end 2 thereof is inserted between the usual circular rotary supporting-plate 8 of the phonograph 9 and the record disk 10 mounted upon said plate, the arms 4 being tapered, as above described, in order to facilitate such insertion. Said end 2 is forced inwardly toward the 60 center of the disk or toward the centering stud 11 which projects upwardly from the center of the plate 8 through the disk 10 (slot 3 in the end 2 being provided for the reception of said stud) until the disk 11 is 65 elevated from said plate and is supported entirely upon the end 2 of the device, when said disk may evidently be lifted from said plate. Thus the removal of a record disk 70 may be effected with ease and expedition, 75 and by the employment, if desired, of only one hand. The non-abrasive strips 5 are provided in order to guard against scratching or otherwise marring the surfaces of the record disks during the insertion of the de- 80 vice thereunder. Said strips are preferably of transversely arched form so that, upon the insertion of the device, as above stated, the same will not engage the edge of the disk to prevent further insertion of the de- 85 vice. The end 6 of the device is designed for employment as a duster, the same being especially applicable in the cleaning of the surfaces of the record disks preparatory to their arrangement in the phonograph for 90 rendition.

While I have shown what I deem to be the preferable form of my device I do not wish to be limited thereto as there might be various changes made in the details of 95 construction and arrangement of parts described without departing from the spirit of the invention comprehended within the scope of the appended claim.

Having described my invention what I 100 claim as new and desire to secure by Letters Patent is:

2

A device for removing phonographic record disks comprising a bar having a bifurcated end; and non-abrasive transverse strips secured to both sides of said bifurcations intermediate their ends, the said strips being transversely arched in form, substantially as described.

In testimony whereof I have signed my name to this specification in the presence of two subscribing witnesses.

FRANK A. SCHIMANSKI.
